SUPERHETERODYNE RECEIVER

George L. Beers, Collingswood, N. J., assignor to
 Radio Corporation of America, a corporation of
 Delaware

Application December 29, 1933, Serial No. 704,437

7 Claims. (Cl. 250—20)

My invention relates to radio receivers and particularly to receivers of the superheterodyne type.

As explained somewhat in detail in my Patent 5 1,915,483, superheterodyne receivers are subject to various types of interference such as image frequency response, reception of signals heterodyned by harmonics of the local oscillator frequency, and the simultaneous reception of signals from two 10 stations, the carriers of which differ in frequency by the intermediate frequency. Many expedients have been resorted to for eliminating or reducing such interference, the above-mentioned patent being an example.

15 The most commonly employed expedient is the utilization of a selecting circuit or network, such as a tuned radio frequency amplifier, between the antenna and the first detector. Present practice is to make this selecting circuit as sharply tuned 20 as possible consistent with the communication band it is desired to receive, both for the purpose of reducing image frequency response and similar interference to a minimum, and for the purpose of increasing the over-all selectivity of the receiver.

25 In a uni-controlled receiver, this requires the simultaneous tuning of a plurality of sharply tuned circuits, and it has been found difficult to keep the various tuning devices properly aligned. It has been found especially difficult to make the 30 oscillator "track" with the sharply tuned circuits. By "tracking" is meant causing the oscillator frequency to continuously differ from the tuning of the tuned circuits by a fixed value equal to the 35 intermediate frequency as the receiver is tuned over its frequency range.

An object of my invention is to provide an improved superheterodyne receiver that shall be free from interference of the above mentioned 40 types.

A further object of my invention is to provide an improved superheterodyne receiver employing variable inductance tuning.

A still further object of my invention is to provide an improved method and means for preventing interference, of the above-mentioned types, in a superheterodyne receiver without introducing difficulties in aligning the tuning devices of the receiver.

50 In practicing my invention, I provide a superheterodyne receiver with a preselecting circuit in the form of a variable band-pass filter having a "pass" range which is narrow enough to prevent the various forms of superheterodyne interference, but which is so wide that there can be no

difficulty in aligning the tuning devices. The "pass" range is also so wide that it does not contribute to the adjacent channel selectivity of the receiver. In a preferred embodiment of my invention, the band-pass filter comprises a plurality of variable iron-core inductances, these inductances being variable simultaneously with the tuning of the oscillator.

By the "pass" range of the above-mentioned variable band-pass filter is meant that frequency 10 range or band which lies between the upper and lower cut-off points of the filter at any given filter setting. This definition also applies to any tuned circuit or system designed to pass a band of frequencies for a given adjustment or setting there- 15 of. The "pass" range of a circuit may also be defined as the frequency band within which the circuit will pass signals with minimum attenuation.

Other objects, features, and advantages of my 20 invention will appear from the following description, taken in connection with the accompanying drawing, in which

Fig. 1 is a schematic diagram of a radio receiver embodying my invention; 25

Fig. 2 is a view showing the construction of a portion of the apparatus shown in Fig. 1; and

Fig. 3 is a set of curves showing certain characteristics of my improved receiver.

Referring to Fig. 1, the radio receiver comprises a first detector 1 having an input circuit which is coupled to an antenna 3 through a variable band-pass filter indicated generally at 5. The input circuit of the first detector includes a resistor 7 which is the terminating impedance of the band-pass filter. A coupling coil 9 and a self-biasing resistor 11 are connected in series with the terminating impedance, the self-biasing resistor 11 being shunted in the usual manner by by-pass condenser 13. A pentode tube such as 30 the type known as the RCA-57 has been found satisfactory for use as the first detector. 35

In order to convert incoming radio frequency signals to a predetermined intermediate frequency, an oscillator 15 is provided which is coupled 45 to the first detector 1 through the coupling coil 9. The frequency of the oscillator output is varied by means of a variable inductance coil 17 in the tuned oscillator circuit as will be more fully described hereinafter. The oscillator feed-back 50 coil 16 and the coupling coil 9 are preferably wound over the cathode or low potential end of the coil 17.

The intermediate frequency signal output of detector 1 is fed to an intermediate frequency 55

amplifier 19 through an intermediate frequency transformer 21. The transformer 21 is tuned by means of condensers 23 and 25 shunting the primary and the secondary windings, respectively, to function as a band-pass filter having a "pass" range of sufficient width to pass the communication band, which band may be the carrier and both side bands or the carrier and only one side band.

10 The output of the intermediate frequency amplifier 19 may be fed to another amplifier or to a second detector through an intermediate frequency transformer 27 tuned to function as a band-pass filter in the same manner as the transformer 21.

15 The variable band-pass filter 5 forms a pre-selecting circuit which is provided solely for the purpose of preventing the various types of superheterodyne interference previously noted. While 20 the band-pass filter is referred to as a "preselecting" circuit, it does not preselect in the sense that it selects the particular station to be received. It merely selects a frequency band within which 25 there is no signal that can be heterodyned to produce an interfering signal. All adjacent channel selectivity is provided by the superheterodyne oscillator 15 and the tuned intermediate frequency 30 transformers 21 and 27. That is, the actual station selecting is done by varying the frequency of the oscillator output. This will be more clearly 35 understood by referring to specific values which are employed in one receiver embodying the invention. In this particular receiver, the intermediate frequency is 175 kilocycles and the "pass" range of the band-pass filter 5 is 75 kilocycles.

40 Since this particular receiver is designed to receive radio signals having a communication channel of approximately 10 kilocycles in width, the "pass" range of the intermediate frequency 45 transformers is made 10 kilocycles wide. It will be understood, of course, that where the communication channel is wider, as in the case of high fidelity transmission, the "pass" range of the intermediate frequency transformers will be correspondingly greater to permit high fidelity 50 reception. For example, they may have a "pass" range of 20 kilocycles.

55 It will be evident that with a "pass" range of the order of 75 kilocycles, the band-pass filter can not contribute to the adjacent channel selectivity where the frequency spacing of adjacent carrier waves is 10 kilocycles as it is in the broadcast band. On the other hand, since the "pass" range of the filter is less than the intermediate frequency 60 of the receiver, it will prevent image response and the various other types of superheterodyne interference hereinbefore mentioned. For example, two incoming signals can beat together in the first detector to produce an interfering signal at the intermediate frequency only if the filter passes signals differing in frequency by an amount equal to the intermediate frequency. If the filter is designed to have such attenuation characteristics as to substantially prevent the 65 passage of two signals differing in frequency by an amount equal to the intermediate frequency, it will also prevent any substantial image frequency response providing the cut-off of the filter is sharp enough, it being necessary that the undesired signal be attenuated more for keeping image frequency interference at a low value than for keeping the other forms of interference at a 70 low value.

75 Referring now to the design of the band-pass filter 5, it comprises a plurality of filter sections,

each section including a tunable series inductance coil having inductance L_1 and identified by the letter L_1 , and a tunable shunt circuit connected in shunt thereto. The tunable shunt circuit includes a condenser C_2 , having capacity C_2 (530 micro-microfarads in the particular receiver being described), connected in parallel with an inductance coil having a value L_2 and identified by the letter L_2 . The band which the filter passes is determined by the position of a plurality of 10 movable cores 29 and 31, respectively, which change the inductance values of the coils as they are moved with respect thereto. Each movable core 31 comprises, in addition to an iron core 33, a copper tube 35 fastened to the end of 15 the iron core 33 for providing a wider change in the inductance. This feature of the invention will be more fully explained hereinafter, in connection with Fig. 2. In the specific embodiment being described, the coils L_1 are variable between 20 447 and 1020 micro-henries and the coils L_2 are variable between 26.2 and 158 micro-henries.

25 In accordance with the usual filter practice, the reactance units of the terminating shunt circuits are given twice the impedance values of the reactance units of the other shunt circuits in order to properly terminate the filter. The output end of filter 5 is terminated by the resistor 1, which, in the above-mentioned embodiment of the invention, has a resistance value of 4000 ohms, this 30 also being the terminal impedance of the filter.

35 A variable inductance coil L_3 is provided for tuning the antenna and in the present embodiment is variable between 100 micro-henries and 755 micro-henries. The input end of the filter is 40 connected across variable inductance coil L_3 , this connection preferably being made through a resistor 37 which, in the above-mentioned embodiment, has a value of 2000 ohms.

45 The antenna coil L_3 , the filter coils L_1 and L_2 , and the oscillator coil 17 may be adjusted simultaneously by means of a common control device indicated at 39.

50 In order to make the receiver tune properly when connected to different antennas, a variable condenser 41 is connected in series with the antenna. If the receiver is adjusted to tune properly when employing a certain antenna with the condenser set at a certain value, the condenser will be adjusted to a larger value of capacity for 55 proper tuning, if the receiver is connected to an antenna having a smaller capacity than the first mentioned antenna.

55 The filter structure will be better understood by referring to Fig. 2. In this figure, only a portion of the variable inductance coils have been shown in order to simplify the drawing. Preferably, all the cores of these inductance coils are supported from a suitable supporting structure, such as a plate 43. The inductance coils L_1 , L_2 , 60 L_3 and 17 are mounted underneath the movable cores so that the cores may be moved into or out of the coils by moving the plate 43 up or down. The position of plate 43 may be controlled in any suitable manner, as by means of a cam and slow 65 motion mechanism (not shown).

70 The cores 31 comprise the section 33 of magnetic material in the form of a cylindrical rod and the tube 35 of conducting material such as copper fastened to the end of the magnetic core 75 section. This type of core is utilized in order to obtain greater change in the inductance values of the coils than possible with the iron core alone, the inductance value being minimum when the copper tube is completely inside the coil and 75

maximum when the iron core section is completely inside the coil. The change in inductance required for the series filter coils L_1 is not so great as that required for the shunt coils so that the 5 use of iron cores alone has been found to be satisfactory.

The magnetic material for the above-described cores preferably consists of finely comminuted iron, the small iron particles being held together 10 by a binder having insulating properties for reducing eddy current losses.

The value of the oscillator inductance coil L_7 may be varied by means of a core 45 supported from the plate 43 and movable simultaneously 15 with the cores of the filter coils and antenna tuning coil. The core comprises a cylindrical rod 47 of magnetic material and a cylindrical member 49 of conducting material such as brass or copper fastened to the end thereof.

20 It is desirable to have the frequency of the oscillator change in such a way as the receiver is tuned over the frequency range thereof that the oscillator frequency will always be higher than the midpoint frequency of the filter "pass" 25 range by an amount equal to the intermediate frequency. As previously mentioned, this is referred to as causing the oscillator to "track" with the selecting circuit. In order to make the oscillator frequency change in this manner, the 30 core of the oscillator inductance coil is specially shaped, whereby the inductance of the oscillator tuned circuit (consisting of coil L_7 and a condenser 48) changes in the required manner as the receiver is tuned over the frequency range for 35 which it is designed.

In the particular apparatus illustrated, the magnetic portion 47 of the core is cylindrical, the same as the other magnetic cores, while the brass section 49 is turned down to a reduced diameter 40 near the point where it is attached to the portion 47 so that this brass section is substantially conical in shape.

The above described core shape for the oscillator inductance coil is made such that the oscillator will track with an ideal filter. As a matter 45 of fact, it is very difficult to make an oscillator track perfectly with a filter as filters are constructed in a factory under quantity production conditions. In production, there will be certain 50 variations in the inductance of the filter coils, and other variations in the filter circuit which will cause the "pass" range of the filter to vary, as the receiver is tuned over its frequency range, in a way which can not be readily controlled.

55 Therefore, it is one feature of my invention to make the "pass" range of the filter so wide that such variation in the filter characteristics will not cause any detrimental effect on the operation of the receiver. This will be better understood by referring to Fig. 3.

Fig. 3 illustrates one case where a receiver embodying my invention is tuned to a signal at the low end of the broadcast band and another case 60 where the receiver is tuned to a signal near the upper end of the broadcast band.

In the first case illustrated, the receiver is tuned to a signal having a carrier frequency of 625 kilocycles, that is, this signal is being heterodyned to the intermediate frequency signal of 175 kilocycles by the oscillator frequency of 800 kilocycles. It will be noted that the band-pass filter 5 is so adjusted with respect to the oscillator 15 that the signal, which is being received, falls at the midpoint of the "pass" range of filter 75

5, the filter characteristic being indicated by the curve A.

Referring, now, to the second case, the receiver is tuned to a signal having a carrier frequency of 1375 kilocycles, this signal being heterodyned to the intermediate frequency signal of 175 kilocycles by the oscillator output having a frequency of 1550 kilocycles. It will be noted that the signal being received at this end of the broadcast band does not fall at the mid-point of the "pass" 10 range of the filter, the filter characteristic being indicated by the curve B.

However, in spite of the fact that the tuning of the oscillator has changed 10 or 20 kilocycles with respect to the mid-point of the filter "pass" 15 range, the signal is received perfectly without any side-band attenuation. It will be understood that the shift of the midpoint of the filter "pass" range might be in the opposite direction to the one illustrated in Fig. 3; or the midpoint of the 20 "pass" range may shift with respect to the received signal in an irregular fashion, at one time being below the signal frequency and another time being above the signal frequency.

In some cases it may be desirable to extend 25 the effective tuning range of filter 5 by so adjusting it with respect to oscillator 15 that a signal being received at the low end of the frequency band falls on the low frequency side of the midpoint of the pass range of filter 5 (instead of at the midpoint), while a signal at the high end of the frequency band falls on the high frequency side of said midpoint.

Attention is called to the fact that I have chosen a filter design such that the cut-off characteristic of the filter at the end of the "pass" 35 range which is adjacent to the oscillator frequency is sharper than the cut-off characteristic at the other end of the "pass" range. In the receiver illustrated, since the oscillator frequency is higher than the signal frequency, the cut-off 40 of the filter at the high frequency end of the "pass" range is sharper than the cut-off at the other end. This permits the use of a simple filter design and, at the same time, provides maximum attenuation at the point where it is most desirable 45 for the purpose of reducing image frequency response. It will be understood, of course, that image frequency response is caused by the oscillator being tuned to a frequency which is half way between a desired signal and an undesired 50 signal, and that this is the most serious form of the various types of superheterodyne interference heretofore mentioned.

One advantage of my receiver design over that 55 of conventional superheterodyne design will be apparent from a comparison of the curves A and C in Fig. 3, where curve C shows the selectivity of the selecting or radio frequency amplifier circuit in a conventional superheterodyne receiver. It will be seen that the conventional selecting circuit is tuned rather sharply, having a "pass" range of only about 10 kilocycles. A "pass" range of 10 kilocycles is, of course, the minimum "pass" 60 range permissible for a circuit which does not cut off any of the signal side-bands where the communication channel is 10 kilocycles in width.

A selecting circuit, having the characteristic shown by curve C contributes to the adjacent 65 channel selectivity of the receiver but it also greatly increases the difficulty in "tracking" the oscillator with the selecting circuit. For example, if the oscillator frequency shifts even 2 or 3 kilocycles with respect to the midpoint of the resonant curve C in tuning from one end of the broad- 70 75

cast band to the other end, the receiver does not operate properly as the selecting circuit attenuates a portion of the communication band. Furthermore, a plurality of selecting circuits, tuned to give the overall characteristic shown by curve C, are difficult to align properly, as previously mentioned.

There is a further advantage in my receiver design in that a variable band-pass filter having variable inductance coils is much easier to construct when its "pass" range is wide as specified in the foregoing description. One reason for this is that the individual parts of the filter may depart somewhat from their preferred relationship as the filter is being tuned, and the resulting irregularities in the filter characteristics will not be detrimental. Another reason is that, by making the "pass" range wide, the inductance coils (especially the series coils) need not be given unreasonably large values.

From the foregoing description, it will be apparent that various modifications may be made in my invention without departing from the spirit and scope thereof, and I desire, therefore, that only such limitations shall be placed thereon as are necessitated by the prior art and are set forth in the appended claims.

I claim:

1. In a radio receiver of the superheterodyne type, a signal collecting means, a first detector, a circuit tunable over a predetermined frequency range coupling said signal collecting means and said detector, an oscillator coupled to said first detector for heterodyning an incoming signal to a signal having an intermediate frequency, said oscillator including a tunable circuit comprising an inductance coil having a core which is movable with respect thereto, and a uni-control means for tuning said first circuit and for causing relative movement between said coil and said core simultaneously whereby the tuning of said circuit and the frequency of the oscillator output may be varied simultaneously, said core being so shaped that over said frequency range the frequency of the oscillator output always differs from the tuning of said first circuit by an amount substantially equal to said intermediate frequency.

2. In a radio receiver, a radio frequency system coupled thereto and tunable throughout a predetermined frequency range, means including an oscillator for converting a radio frequency signal to an intermediate frequency signal, said converting means including a tunable circuit comprising a variable inductance coil having a core consisting of a magnetic section and a non-magnetic section of conducting material, an intermediate frequency system tuned to pass said intermediate frequency signal, said radio frequency system comprising a multi-section band-pass filter, each filter section including a variable inductance coil having a core consisting of a magnetic section and a non-magnetic section of conducting material, and a uni-control means for varying said filter and said first variable inductance coil, said first core being so shaped that over said frequency range the frequency of the oscillator output always differs from the tuning

of said radio frequency system by an amount substantially equal to said intermediate frequency.

3. In a superheterodyne receiver, a radio frequency system comprising a band-pass filter tunable over a predetermined frequency range, means including a tunable oscillator for converting a radio frequency signal to an intermediate frequency signal, and an intermediate frequency system tuned to pass said intermediate frequency signal, said filter including tuning means comprising series and shunt inductance coils provided with variable cores, and common means for moving said cores simultaneously in predetermined relation to each other to pass a band of frequencies which is wide compared with the band of frequencies passed by said intermediate frequency system, and means in said filter providing a cut-off characteristic which is sharper at that end of the pass range of the filter which is the closer to the frequency of said oscillator.

4. The invention according to claim 1 characterized in that said core consists of a magnetic core section and a non-magnetic core section of a material which is an electrical conductor, said last section being tapering in cross section.

5. The invention according to claim 1 characterized in that said core consists of a magnetic core section and a non-magnetic core section of material which is an electrical conductor, said last section being substantially conical in shape with its smaller end adjacent to said magnetic section.

6. The invention according to claim 2 characterized in that the non-magnetic section of said first core is of non-uniform cross-section.

7. In a superheterodyne receiver, a radio frequency circuit tunable throughout a predetermined frequency range and an intermediate frequency circuit, said radio frequency circuit including a multi-section band pass filter designed to pass a band of frequencies which is wide with respect to the band of frequencies passed by said intermediate frequency circuit, each section of said filter comprising a series inductance coil, a shunt inductance coil, and a condenser connected across said shunt inductance coil, each of said series inductance coils having a magnetic core and each of said shunt inductance coils having a core comprising a magnetic section and non-magnetic section of conducting material, each inductance coil and magnetic core being relatively movable, means including an oscillator for converting a radio frequency signal to an intermediate frequency signal, said oscillator including a tunable circuit comprising a variable inductance coil having a core consisting of a magnetic section and a non-magnetic section of conducting material, uni-control means for producing relative movement of said inductance coils and said cores simultaneously, said last-named core being so shaped that over said frequency range the frequency of the oscillator output always differs from the tuning of said radio frequency circuit by an amount substantially equal to said intermediate frequency.

GEORGE L. BEERS.
